UNITED STATES PATENT OFFICE

2,488,575

AUTOMATIC RADIO TUNER

Ivan Andersson, St. Petersburg, Fla.

Application August 27, 1947, Serial No. 770,914

6 Claims. (Cl. 161—1)

1

The present invention relates to means for automatically operating a number of electric coils at a prearranged time. The object being to arrange these coils to automatically operate a number of switches or push buttons of a radio-receiving set so that a number of broadcasting stations may be automatically tuned in at a prearranged time. It may also be used for automatically operating switches for signals or starting machinery at a prearranged time.

To accomplish this I provide a body with a center hole and a number of radial slots arranged around the center hole. Toothed racks are resting in these slots and capable of being moved out and in from and to the center and held in any desired position. Each of these racks is provided with a projection adapted to actuate one of a number of electric contact members mounted on a disk carried by the hour hand shaft which is rotated by a clock work. The position of the aforesaid slots are arranged to correspond with the hours or fraction of hours of the clock which corresponds with the time. Means are provided to move and set any of these racks at any time to any desired position where the projection on the rack will strike an electric contact member, which revolves past said projection at the time corresponding to the position of the slot. This will cause the electric contact member to close an electric circuit which will energize an electric coil arranged to operate a push button switch or otherwise to tune in a certain radio station. Means are provided to automatically cause the racks to move back into their original or inoperative position.

The accompanying drawings illustrate the invention where:

Fig. 1 is a front view, and

Fig. 2 a rear view of the arrangement.

Fig. 3 and Fig. 4 are fractional views of rack, pawl, pawl support and pawl operating cam.

Fig. 5 is a side view, partly in section, of the device.

Fig. 6 and Fig. 7 are detail views of the rack and pawl operating means.

Fig. 8 is a top view of two racks, the pawls and the spring for holding the pawl in engagement with the rack.

Fig. 9 is a plan of the device partly in section.

Fig. 10 is a rear view of the rotating disk with contact members.

Fig. 11 is a section on line 11—11 of Fig. 10 and

Fig. 12 is a diagrammatic view of the electric connections between the contact rings and the coils.

2

The body 1, Fig. 5, consists of two slotted plates 2 and 3 and a spacer 4 which supports rods 5 and helical springs 6. Spacers 7 are held at the periphery of the body between the slotted plates. The toothed racks 8 which are provided with projections 105 are held in position between the slotted plates 2 and 3 by means of slots 88 in the racks which embrace the spacer 4 and by the bent over outer ends 9 of the racks which 10 slide between the plates 2 and 3 and abutting against the helical springs 6. Holes 89 in the bent over ends of the racks allow the rods 5 to pass through. The pawls 10 are pivoted on brackets 11 which are mounted on plate 3 and 15 are normally kept in engagement with the racks by springs 12, Figs. 2, 7 and 8, but automatically disengaged by cam 119, which is mounted on the periphery of the rotating disk 13. The rotating contact disk 13, Figs. 5, 10 and 11, carries 20 the contact springs 14 which normally are out of engagement with the contact rings 16, and contact spring 15, shown in broken lines in Fig. 11, which is always in contact with ring 17, Fig. 12. The pins 90 are carried by the springs 18, 25 which when bent inwards transmit the motion to springs 14 by plugs 91 of non-conductive material carried by springs 18. The contact rings 16 and 17 are mounted on a disk 19 of non-conducting material which is fixed and supported by the clock 20. The clock 20 is supported by the fixed shaft 21 in the rear which is carried by the bracket 22. The slotted body 1 is supported by the angle 23 and braced by rods 24. The rotatable arm 25 is mounted on the fixed shaft 21 and carries bell crank 26 and lever 27. The pawl 28 is pivoted on one arm 29 of the bell-crank and is provided with pin 30 and spring 31, Fig. 6, which forces the pawl in engagement with the rack 8 and moves it inwards one tooth by the solenoid 35 when energized, through links and levers 37, 38, 39 and 40. On neutralizing the solenoid the pawl 28 swings outwards by the action of the helical spring 36, which moves the armature 41 out and operates aforesaid links 45 and levers causing one end of the pawl to strike the cross rod 32 which moves the pawl 28 out of engagement with the rack, thereby freeing the rotatable arm 25 and allowing it to be rotated freely on the shaft 21. The lever 27 is also pivoted to the arm 25 the one end of which carries a pin 34 (Fig. 7) which will on swinging forward strike the pawl 10 and release the rack. This movement is caused by the solenoid 42 being energized and attracting the armature 43 50 which operates the lever 27 through links and 55 which operates the lever 27 through links and

levers 44, 45, 46 and 47. On neutralizing the solenoid 42 the spring 48 will cause the pin 34 through aforesaid links and levers to be retracted to its normal position. On the arm 25 a gear 49 is fastened concentric with the shaft 21, the center line of which coincides with the center of the hole in the body 1. This gear is in engagement with gear 50 which engages pinion 51 mounted on spindle 52, which spindle also carries a knob 58 for rotating the spindle and gears for positioning the arm 25 when a rack is to be set. To be able to see when the arm is in the desired position a hand 53 is mounted in front of the dial 55, Figs. 1 and 9, on a spindle 54, Fig. 5, which runs through a central hole in the shaft 21 and hour shaft 56 and minute shaft 57 of the clock. This spindle 54 is geared by miter gears 58 and 59 to a shaft 60 which again is geared by miter gears 61 and 62 to shaft 63 on which is mounted gear 50 which rotates with the same speed as arm 25, Fig. 2.

To operate the solenoid a modified telephone dial is used which consists of a circular plate 64 with a number of finger holes 65, as many as there are relays provided for, plus one for canceling the setting of a rack. In the present example there is arranged for 5 relays which are identified by different colors. The colors are shown on a dial behind the finger holes. A part of the front of the housing 66 is shown in broken lines, Fig. 1, with the opening 67 in front of the holes 65. This opening 67 limits the movement of the finger and the dial plate and allows the correct number of electric impulses corresponding to the number of holes on return of the dial plate to normal position. The arrangement of the telephone dial is shown more or less diagrammatic in the rear view Fig. 2.

Behind the dial plate 64 which is carried by shaft 74 is mounted a plate 68 with colored areas behind the finger holes which moves with the dial 64. Behind is rigidly mounted a circular plate 69 with a recess 70 and a rigid pin 71 which protrudes through a slot 72 in a plate 73 loosely mounted on shaft 74. This plate carries a pawl 75 which engages the teeth of a ratchet 76 which is loosely mounted on the shaft 74. Another pawl 77 pivoted to the frame 78 prevents the ratchet to turn on dialing, the pawl 75 just slipping over the teeth while the helical spring 79 is tightened, one end which is attached to the dial shaft 74 and the other end to the frame. A gear 80 is mounted on the ratchet and turns with it and is engaging a smaller gear 81 mounted on a spindle 82 which carries a cam 126 on which rides a contact spring 83 which makes and breaks an electric circuit when it rotates. As the ratchet only rotates in one direction the cam will only rotate in one direction, that is on the return movement which is to the same amount it was first rotated. This will cause electric impulses to be sent through one solenoid which is the one which operates the rack by the pawl 28.

However, to move the rack to the correct setting it must first be returned to its normal or zero position and this is accomplished by providing the disk 73 with a recess 84. When turning the dial plate 64, Fig. 2, with plate 69 which carries a pin 71 moving in a slot 72 of the loosely mounted plate 73 this last named plate is retarded until pin 71 has reached the other end of the slot 72 when it moves along with disk 69 and with the recesses 70 and 84 in alignment, the lever 85 can now snap into the recesses and cause contact to be made between the two contact springs 86.

and 87. The electric current is closed and an electric impulse sent through the solenoid which operates the lever 27 releasing the rack and allowing it to return to its zero position.

On return of the dial the loosely mounted disk is retarded again and the disk 69 moves ahead so the recesses become out of alignment and there is no movement of lever 85, no contact between the two springs 86 and 87, and so no electric impulse is sent through the solenoid for operating lever 27 and rack pawl 10. On rotating the dial the electric current impulses run from supply wires 92 and 93 through make and break contact 86 and 87 through wire 95 contact 93 contact ring 97 solenoid 42 contact ring 98, contact 99 and wire 100. On return movement of the dial the electric current impulses run from supply wires 92 and 101 through make and break contact 83 and 94 through wire 102, contact 103, contact ring 104, through solenoid 35, contact ring 98, contact 99 and wire 100.

On actuating a pin 90 on contact with a projection 105 of a rack 8, a contact spring 14 is raised and makes contact with one of the concentric contact rings 16 and an electric circuit is closed, Fig. 11. The current runs through the supply wire 106 to contact ring 17 through the contact spring 15, and the raised contact spring 14 to a contact ring 18, through a wire 103, a coil 107 back to the electric supply by the wire 108, Figs. 10, 11 and 12. As an example the coils 107 are shown in a position with their armatures in front of the push buttons 103 of a radio 109.

The shaft 21 is provided with holes 110 for the passage of the wires 106. The racks 8 have projections 111 sticking out through the slots in the dial 55, Fig. 1, to indicate what stations have been dialed. The hour shaft 56 carries gear wheel 117 which gears to the clock and minute shaft 57 carries pinion 112 also geared to the clock. For the setting of the clock, spindle 114 is passed through a hole in shaft 21 and carries a pinion 113 at one end for engaging pinion 112 and a knurled button 115 at the rear end. A helical spring 116 keeps the pinion 113 out of engagement normally, Fig. 5.

The body 1 on its front side has a dial 55 with slots 121, Fig. 1, coinciding with the slots 120, Fig. 2, in the body, through which projections 111 on the racks 8 protrude and indicate the positions of the racks. By arranging a number of concentric annular bands 125 on the dial in different colors which indicate different broadcasting stations, it is possible to observe the position and the broadcasting station for which the rack has been set. The dial is graduated so that the slots coincide with the graduations which are generally for hours and quarter hours on a twelve hour dial. The hour shaft 56 and the minute shaft 57 carry the usual hands 122 and 123 in front of the dial 124, which has the regular hour and minute divisions.

I claim:

1. A fixed body having a center hole and radial slots around this center hole and toothed racks arranged to slide in said slots, springs to push said racks outward from the center, stops to limit the movement of the racks, pawls arranged to engage the teeth of said racks and hold them in required positions, a fixed shaft, an arm mounted on the fixed shaft and capable of being rotated on said shaft, means for moving said racks in toward the center, means for releasing said racks and allow them to move outward to the stops, said two means arranged on aforesaid rotatable

arm mounted on the fixed shaft, allowing said means to be swung around with said arm to any position in front of a rack to be operated by said means, and projections on the racks for actuating electrical contact members.

2. A fixed body having a center hole and radial slots around this center hole, toothed racks arranged to slide in said slots, springs to push said racks outward from the center, stops to limit the movement of the racks, pawls arranged to engage the teeth of said racks and hold them in required position, a fixed shaft, an arm mounted on the fixed shaft and capable of being rotated on said shaft, a pawl pivoted to a bell crank mounted on the rotatable arm and adapted to be brought into engagement with the teeth of a rack for the purpose of moving the rack towards the center, a solenoid with an armature mounted on the aforesaid arm, levers and links connecting the above said bell crank to the armature of the solenoid, means for energizing the solenoid, by electrical impulses, spring for returning the armature and parts connected to their original position, and projections on the racks for actuating electrical contact members.

3. A fixed body having a center hole and radial slots around this center hole, toothed racks arranged to slide in said slots, springs to push said racks outward from the center, stops to limit the movement of the racks, pawls arranged to engage the teeth of said racks and hold them in required positions a fixed shaft, an arm mounted on the fixed shaft and capable of being rotated on said shaft, a lever pivoted on said arm and carrying a pin adapted to be brought into engagement with one of said pawls and move it to release the rack, a solenoid with an armature mounted on the aforesaid rotatable arm, levers and links connecting aforesaid lever to the armature of the solenoid, means for energizing the solenoid by electrical impulses, spring for returning the armature and parts connected to their original position, and projections on the racks for actuating electrical contact members.

4. A fixed body having a center hole and radial slots around this center hole, toothed racks arranged to slide in said slots, springs to push said racks outward from the center, stops to limit the movement of the racks, pawls arranged to engage the teeth of said racks and hold them in required positions, a fixed shaft, an arm mounted on the fixed shaft and capable of being rotated on said shaft, means for moving said racks in toward the center, means for releasing said racks and allow them to move outward to the stops, said means carried on the arm mounted on the fixed shaft, a gear rigidly mounted on said arm and concentric with the shaft, gears mounted outside and clear of the rotating arm but in mesh with the first said gear, and a knob for turning the gears and rotating the arm on the fixed shaft, a spring and a roller pressing between the teeth of the fixed gear mounted on the arm to insure a correct position of the arm when a rack is to be operated.

5. A fixed body having a center hole and radial

slots around this center hole, toothed racks arranged to slide in said slots, springs to push said racks outward from the center, stops to limit the movement of the racks, pawls arranged to engage the teeth of said racks and hold them in required positions, a fixed bracket, a fixed shaft rigidly supported by said bracket, a rotatable arm mounted on said shaft, means for moving said racks in toward the center, means for releasing said racks and allow them to move outward to the stops, said two means arranged on aforesaid rotatable arm mounted on the fixed shaft, allowing said means to be swung around with said arm to any position in line with a rack to be operated by said means a clock rigidly supported on said shaft, a plate of non-conducting material and with a center hole supported by the clock, hour and minute shafts driven by the clock protruding through the center holes in the first named body and last named plate, concentric metal rings mounted on the last named plate of non-conducting material, a member rigidly mounted on the hour shaft between the plate and the racks, and rotating with it, electric contact members mounted on the last named member which is mounted on the hour shaft said contact members adapted to be actuated by any projection on the racks and pressed against one of said concentric metal rings, and a cam mounted on said member for releasing the rack by actuating the pawl that holds the rack in position.

6. A fixed body having a center hole and radial slots around this center hole, toothed racks arranged to slide in said slots, springs to push said racks outward from the center, stops to limit the movement of the racks, pawls arranged to engage the teeth of said racks and hold the racks in the required positions, a rigid bracket, a fixed shaft supported by said bracket, an arm mounted to rotate on said shaft means for moving aforesaid racks in toward the center, means for releasing said racks and allow them to move outward to the stops, said two means arranged on aforesaid rotatable arm and allowing said means to be swung around with the arm to any position in line with a rack to be operated by said means, a fixed gear mounted on the arm, concentric with the shaft, a central hole through said shaft, a spindle located in said hole and extending from the back to the front of the body, a gear mounted on the rear end of the spindle and geared to the fixed gear on the arm, an indicating hand mounted on the other end of the spindle rotating in unison with the arm in front of the body.

55 IVAN ANDERSSON.
